DESIGN FOR A CASING FOR A CARD INDEX

Reginald B. Meller, Oakland, Calif., assignor to Associated Patents Corporation, San Francisco,
Calif., a corporation of California

Application April 27, 1934, Serial No. 51,537

Term of patent 7 years

To all whom it may concern:

Be it known that I, REGINALD B. MELLER, a citizen of the United States, residing at Oakland in the county of Alameda and State of California, have invented a new, original, and ornamental Design for a Casing for a Card Index, of which the following is a specification, reference being made to the accompanying drawing, forming part thereof, and in which Fig. 1 is a perspective view of a casing for a card index showing my new design and Fig. 2 is a front elevation of the same.

I claim:—

The ornamental design for a casing for a card index, as shown.

REGINALD B. MELLER.
